US00D551246S

(12) **United States Design Patent** (10) **Patent No.:** **US D551,246 S**
Gusmorino et al. (45) **Date of Patent:** **** Sep. 18, 2007**

(54) **ICON FOR A PORTION OF A DISPLAY SCREEN**

(75) Inventors: **Paul Gusmorino**, Seattle, WA (US); **Mark R. Ligameri**, Austin, TX (US); **Jenny T. Lam**, Seattle, WA (US); **Greg S. Melander**, Redmond, WA (US)

(73) Assignee: **Microsoft Corporation**, Redmond, WA (US)

(**) Term: **14 Years**

(21) Appl. No.: **29/228,410**

(22) Filed: **Apr. 22, 2005**

(51) **LOC (8) Cl. 14-04**

(52) **U.S. Cl. D14/492**

(58) **Field of Classification Search ... 715/500.1-501.1, 715/526, 530-31, 539, 708, 711, 717, 723, 715/726, 733, 738, 753, 762, 763-4, 767-69, 715/778-82, 788, 790, 793-94, 797-8, 802-10, 715/835-40, 848-856; 229/117.22; 360/133, 360/135, 97.01-99; 369/272, 273, 280-88, 369/275.1-275.5; D14/485-95; D18/32, D18/33; D19/6, 1; D20/11; D21/324, 329**

See application file for complete search history.

(57) **CLAIM**

The ornamental design for an icon for a portion of a display screen, as shown and described.

DESCRIPTION

The FIGURE is a front view of an icon for a portion of a display screen showing our new design.

The broken line showing of a portion of a display screen is for illustrative purposes only and forms no part of the claimed design.

1 Claim, 1 Drawing Sheet
